DANIEL RISHER, JR., OF DRAVOSBURG, PENNSYLVANIA.

Letters Patent No. 81,946, dated September 8, 1868.

IMPROVED DEVICE FOR LOADING COAL.

The Schedule referred to in these Letters Patent and making part of the same.

TO ALL WHOM IT MAY CONCERN:

Be it known that I, DANIEL RISHER, Jr., of Dravosburg, in the county of Allegheny, and State of Pennsylvania, have invented a new and useful Improvement in Devices for Loading Coal; and I do hereby declare the following to be a full, clear, and exact description thereof.

The coal-strata, on which great reliance is placed for supplies of fuel, in some sections of our country are situate on or contiguous to navigable streams, which afford the means of transportation. In such cases, the coal, when mined and brought to the river-bank, is loaded into barges or boats by being tumbled down a chute, the barge being placed under the lower end of the chute. The barges, when full, are towed to the place where the coal is to be sold or used.

This mode of loading coal, especially soft or bituminous coal, is liable to several serious objections:

Among others, first, the stage of water varying, between high and low-water mark, some thirty feet, more or less, and the mining and loading, to be profitable, being necessarily carried on at all seasons of the year, the chute must be so constructed as to discharge coal into the barge, whatever the stage of water may be. Consequently the coal, when dumped into a barge at low water, has to fall some ten to twenty feet, more or less, from the end of the chute, whereby it is broken and crumbled, so much so as materially to reduce its market value.

Also, as the chute is fixed, it can discharge coal into the barge only at one point. The coal-barges in use on our western rivers are made broad and long, so as to hold generally from ten thousand to twelve thousand bushels of coal. Generally one side of such a barge is loaded, the barge being allowed to drop down-stream to be loaded from end to end; the barge is then reversed, and the other side loaded in the same way. Great difficulty is experienced in thus changing ends, especially as the barge, when half loaded, weighs, say, two hundred and fifty to three hundred tons, and until this is done, the work of mining is liable to be interrupted.

These, and other minor objections, I propose to obviate by the construction of improved apparatus for loading coal into barges; and the nature of my invention consists—

First, in discharging the coal, by a chute, into a coal-hopper, which is hung to a car, such car running on an incline, so adjustable as to bring the hopper near to the level of the boat before dumping the coal therein.

Second, in such construction of a hopper that its load may be discharged from either end, whereby both sides of the barge may be loaded at once, and whereby the necessity of reversing the barge is avoided.

Third, in so hanging the hopper by a rocking-shaft on the car as to admit of its being tipped either way.

Fourth, in so hanging and operating the hopper that it will be self-discharging.

Fifth, in the construction of devices by which the hopper may be made to dump its load automatically from either end; and

Sixth, in the use of balancing-weights, in connection with such devices, for holding the inclined track at any desirable point of adjustment, and securing automatically the return up the incline of the hopper and car when unloaded.

To enable others skilled in the art to make and use my invention, I will proceed to describe its construction and mode of operation, referring by letters to the accompanying drawing, making a part of this specification, in which—

Figure 1 is a perspective view of a portion of my apparatus, showing the frame, incline, car, and hopper, and illustrating their manner of use; and

Figure 2 is like view of the apparatus, which, resting on the car, carries and operates the hopper.

A is any suitable base or foundation, built on the shore of a river where coal is to be loaded. B B are uprights, for supporting the frame C C' C'', all which are of any suitable or convenient construction. The frame C C' is strongly built, and securely attached to its supports B, and its forward end extends out so as to overhang a coal-barge or flat, brought up near to the shore to be loaded. At its rear end, or leading down to it, is a coal-chute, D, of the ordinary construction. To the parallel bars C, of the framework, by head-blocks E, or otherwise, is hung the rear end of the incline α , such incline consisting of parallel track-rails or bars, so made that a car or truck may run up and down or back and forth thereon. This incline α is made of any

convenient length, and its forward end is raised or lowered by a rope or chain, a' , passing over a pulley, b , in the cross-bar C'' , and thence over one or more pulleys, b' , to any convenient place, were the weight of the forward end of the incline a is counterbalanced by a weight, f .

On the incline a is a car or truck, consisting of a truck-frame, c' , and wheels c , the latter being flanged, or otherwise so made that they will follow the inclined track a . Placed across the truck-frame c' is a rocking-shaft, d' , on each end of which is a bearer, d . To these bearers, d , by rods e , is hung the coal-hopper g .

The rocking-shaft d' is operated by a handle, i , which, being turned either way, rocks or tips the bearers d , and so tips the hopper g sufficiently to discharge its contents in the direction in which it is tipped. The hopper g is made with a bottom concave or sloping down toward the middle, from the ends, which are open for convenience in discharging. The track a is pivoted to the frame C , at such point that the car may be run back far enough to bring the hopper g under the lower end of the chute D , for convenience in loading. A rope or chain, e' , leads back from the car to a drum, h , around which it is coiled. Its weight is counterbalanced, as before, by a weight, f , attached to a cord, e'' , coiling around the same drum, h , or around its axle, h' . A pulley may obviously be substituted for the drum and axle. A screen may be placed in the bottom of the chute D , to screen the coal as it slides down.

The mode of operation is then as follows: The lower or down-river end of the barge to be loaded is brought under the forward end of the inclined track a . This latter is then lowered down, more or less, according to the stage of the water in the river, till it is near the discharging-point, and there secured by additional weights, f , resting on a platform, or by supports, or other equivalent means. The car is run back till its hopper g comes under the lower end of the chute D , the coal is tipped down the chute D into it, and the car, with its load, is then run down the incline a , to the proper point, and there unloaded into either side of the barge, by the use of the handle i , in the manner described. The weight f runs the car back for another load, and so on continuously till the barge is loaded. The barge must be dropped down the river of course as its lower or down-river end is filled up. In this way I am enabled to load a barge with coal at any state of water, without the necessity of turning the barge, and without the loss incurred by the coal falling from a considerable height and being crushed, crumbled, or reduced to slack.

But in order to make my apparatus more perfect in its operation, I introduce other devices, in fig. 2. As before, c' represents the truck-frame, d' the shaft, d the bearers, and i the handle. From end to end of the car-frame c' , and through a mortise in the handle i , I pass a circular segmental guide, l . This is notched at several points, as at o , and into these notches drops the locking-bar o' , which is pivoted at one end to the handle i , and at its upper end is raised, when desired, by a tripper, i' , attached thereto, and extending down so far as to be conveniently operated by some suitable projection attached to some of the stationary devices of fig. 1.

In order to shift the centre of gravity of the hopper g , so that it may automatically discharge from either end, as may be desired, I hang it, by clips m , to sliding bars m' , such sliding bars m' being so attached to the bearers d as to be retained in place, but have a limited longitudinal play thereon. These bars, m' , are moved back and forth by a lever, n , attached to both, but slotted at the point where it is pivoted to one. By shifting these sliding bars m' along the bearers d , the centre of gravity of the hopper g , loaded or empty, may be thrown on either side of the centre of suspension. The locking-bar o' falls of its own weight into any notch, o , to which it may be set. The handle i cannot then be shifted either way, and the loaded hopper g , hung as thus described, is carried steadily down the incline a till the tripper i' engages a tripping-projection, by which it is raised. The locking-bar o' is thus lifted from its notch, and there then being nothing to prevent, the hopper g tips automatically in the direction of its heavier side, and discharges its load.

In this way the coal is dumped automatically at the desired point. The weights $f f'$ may be varied as the work may require. Instead of a single track, a , a double track or incline may be used, in which the full car going down may draw up the empty one returning.

What I claim as my invention, and desire to secure by Letters Patent, is—

1. The mode of loading coal into boats, flats, or barges, by sliding the coal down a chute into a hopper hung to a car, and thence running it down an inclined track to the boat, flat, or barge, and discharging it from either end of the hopper into the boat, flat, or barge, substantially as hereinbefore set forth.
2. The tipping coal-hopper g , made with the bottom concave or sloping down toward the middle from the discharging-ends, substantially as and for the purposes hereinbefore set forth.
3. The tipping coal-hopper g , connected by bearers d with a rocking-shaft, d' , mounted on a car or truck, substantially as and for the purposes hereinbefore set forth.
4. Sliding bars m' , carrying a coal-hopper, so connected with the bearers d as that, by a slight longitudinal motion imparted thereto, the centre of gravity of the loaded hopper may be shifted, substantially as and for the purposes above set forth.
5. A tipping-handle, i , attached to the rocking-shaft d' of a coal-loading car, in combination with tripping-devices, constructed and used substantially as and for the purposes hereinbefore expressed.

In testimony whereof, I, the said DANIEL RISHER, Jr., have hereunto set my hand.

DANIEL RISHER, Jr.
